UNITED STATES PATENT OFFICE.

FREDERICK W. LINAKER, OF DUBOIS, PENNSYLVANIA, ASSIGNOR TO THE VULCAN SOOT CLEANER CO., OF PITTSBURG, PA., OF DUBOIS, PENNSYLVANIA, A CORPORATION OF NEW JERSEY.

SOOT-CLEANER FOR WATER-TUBE BOILERS.

1,222,641.

Specification of Letters Patent. Patented Apr. 17, 1917.

Application filed November 13, 1915. Serial No. 61,359.

To all whom it may concern:

Be it known that I, FREDERICK W. LINAKER, a subject of the King of England, residing at Dubois, in the county of Clearfield 5 and State of Pennsylvania, have invented certain new and useful Improvements in Soot-Cleaners for Water-Tube Boilers, of which the following is a specification.

This invention relates to certain new and 10 useful improvements in soot cleaners for water tube boilers.

In water tube boilers of the Stirling type including vertical and semi-vertical water tubes with baffles arranged adjacent the 15 tubes, it has been customary to position the cleaning fluid distributing pipe adjacent the tubes and the outer end of the baffle and during the cleaning operation, the jets of cleaning fluid are directed over the tubes and to 20 ward the fire-box. It will be readily seen that the discharged cleaning fluid while passing in a direction toward the fire-box will act as a damper for the gases and products of combustion and blow the same back 25 into the fire-box and through the fire door and front of the furnace which might cause serious injury to the operator. The present invention, therefore, aims to overcome this defect by a particular construction of cleaning fluid distributing pipe which when in 30 operation, will have jets of cleaning fluid issuing from a plurality of series of jet nozzles or discharge ports that are disposed in different radial planes with respect to the 35 axis of the distributing pipe. It will be seen that when a jet of cleaning fluid is directed over the tubes and toward the fire box, that the blowing and damper effect thereof will be overcome by a jet of cleaning fluid blowing in a different direction and the gases and products of combustion may 40 freely pass over the tubes and reach the outlet stack without being blown back into the fire-box.

With these general objects in view and others that will appear as the nature of the invention is better understood, the same consists in the novel construction, combination and arrangement of parts hereinafter more 45 fully described, illustrated in the accompanying drawings, and then claimed.

In the drawings forming a part of this application and in which like designating

characters refer to corresponding parts throughout the several views:—

55

Figure 1 is a cross-sectional view of a water tube boiler of the Stirling type with the present invention in operative position therein.

Fig. 2 is a sectional view of a portion of 60 the same illustrating a portion of the baffle wall, water tubes and the cleaning fluid distributing pipe.

Fig. 3 is a cross-sectional view of another construction of water tube boiler of the 65 Stirling type with the present invention in operative position therein, and,

Fig. 4 is a view of a plurality of cleaning fluid distributing pipes in which the jet nozzles are arranged in different series and in 70 different radial planes about the pipe.

Referring more in detail to the accompanying drawings and particularly to Fig. 1, the reference numeral 10 designates a boiler setting including banks of tubes A, B 75 and C. Baffles are associated with the banks of tubes and are designated 11, 12 and 13. The baffles 11 and 12 are associated with the bank of tubes A and are so positioned as to positively cause the gases and products of 80 combustion to travel over the tubes A while the baffle 13 is so positioned as to cause the gases to engage the tubes B.

Cleaning fluid distributing pipes 14 are 85 associated with each of the banks of tubes and are preferably of the rotary type, the same being operated by the chains 15 as indicated in dotted lines in Fig. 1. The piping system for feeding the cleaning fluid agent to the distributing pipes 14 includes the 90 main supply 16 communicating with the feed pipe 17 which in turn communicates with the branch pipes 18 and all of the pipes are valve controlled while a drain-cock is provided for the main supply as is indicated. 95

As shown in detail in Fig. 2, the distributing pipe 14 adjacent the baffle 12 may be journaled in the side walls of the boiler setting 10, and has a swivel connection with the branch pipe 18 as is indicated. The distributing pipe 14 is further supported intermediate the ends thereof as by straps or stirrups 19 that engage certain ones of the water tubes A and also support the pipe.

The jet nozzles are positioned in series 105 about the distributing pipe in different ra-

dial planes, and as shown in Fig. 2, the nozzles 20 are in longitudinal alinement on one side of the pipe and extend substantially half-way thereof while the nozzles 21 are 5 positioned on the opposite side of the pipe and are also in longitudinal alinement.

Different forms of the distributing pipe are shown in Fig. 4 and the pipe 14' has the jet nozzles 14" arranged in series of four 10 each with each series alternating as is indicated. The pipe 14² has the jet nozzles 14" arranged in series of six each that alternate and are directed oppositely as is shown. The pipe 14³ has the nozzles 14" arranged 15 eight in each series with the nozzles of one series extending radially in one direction while the nozzles of the other series extend radially at right angles thereto and the pipe 14⁴ has the jet nozzles 14" arranged six in 20 each series, with the series in different radial planes.

It is to be understood that the invention is not confined to the use of jet nozzles as the pipe may be similarly provided with discharge ports and operate in a like manner 25 without departing from the gist of the present invention.

A different type of boiler is shown in Fig. 3 and includes the setting 10 with the banks 30 of tubes A, B and C while baffles 22, 23, 24, 25 and 26 are arranged adjacent the different banks of tubes and associated with each bank of tubes is a cleaning fluid distributing pipe 14 similar to the form shown 35 in Fig. 1 and pipes that are also operated in a like manner. The distributing pipe 14 shown in Fig. 3 has a similar source of steam supply as is described in connection with the showing in Fig. 1.

40 In the operation of the device, the cleaning fluid agent is fed to the distributing pipes 14 by the piping system described and the distributing pipes subsequently revolved by the chains 15. The positioning of distributing nozzles about the periphery of the pipe will not in any manner cause the gases and products of combustion to be blown back into the fire-box and through the doors as the nozzles that are directed opposite to 45 the ones that cause the jets of cleaning fluid to travel toward the fire-box will overcome any dampering effect that the same might have and will insure a proper circulation of the gases and products of combustion. It 50

is of course to be understood that the nozzles 55 14" may be arranged in any desired manner in series and spaced in different radial planes about the periphery of the pipe. In boilers of this construction the gases and products of combustion are primarily re- 60 tained by the first baffle to completely pass over the bank of tubes and with the distributing pipes positioned adjacent the ends of the baffles, there is a tendency when a single stream or jet of cleaning fluid is directed toward the fire-box to force the gases and products of combustion back into the fire-box, but with the present invention, this difficulty is overcome and the gases and products of combustion have a free passage 65 over the first bank of tubes and on to the other ones. The above detail description of the distributing pipes relates more particularly to those pipes that are slightly spaced from the baffles as is indicated; but it is to 70 75 be noted that the distributing pipes 14 that are arranged in close relation to the baffles should preferably have the jet nozzles or outlet ports arranged in longitudinal alinement.

80 While the form of the invention herein shown and described is what is believed to be the preferred embodiment thereof, it is nevertheless to be understood that various forms, modifications and arrangements of 85 the parts may be made without departing from the spirit and scope of the invention as claimed.

89 What I claim as new is:—

A soot cleaner for boiler tubes, including 90 a rotary distributing pipe associated with a bank of boiler tubes, the same being operable by hand-actuated means, a main supply pipe communicating with a feed pipe, a branch pipe, all of said pipes being valve-controlled, 95 said distributing pipe having a swivel connection with said branch pipe, and jet nozzles positioned in two series or sets about said distributing pipe in different radial planes, one set of said nozzles being in 100 longitudinal alinement on one side of said pipe and extending about midway thereof and the second set of said nozzles being positioned also in longitudinal alinement along the other half of the distributing pipe and 105 upon the opposite side of said pipe.

In testimony whereof I affix my signature.

FREDERICK W. LINAKER.
